(57) **CLAIM**

The ornamental design for a keyboard, as shown and described.

DESCRIPTION

FIG. 1 is a front view of a keyboard showing a first embodiment of our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof;

FIG. 8 is a bottom perspective view thereof;

FIG. 9 is a front perspective view thereof with a tablet being attached in a first position;

FIG. 10 is a rear perspective view of FIG. 9;

FIG. 11 is a front perspective view thereof with a tablet being attached in a second position; and,

FIG. 12 is a rear perspective view of FIG. 11.

The features shown in broken lines in the drawings depict environmental subject matter and form no part of the claimed design.
